UNITED STATES PATENT OFFICE.

BARNETT HANSELL, JOHN McCANN, AND SAMUEL McCAMBRIDGE, OF
PHILADELPHIA, PENNSYLVANIA.

IMPROVEMENT IN APPARATUS FOR CUTTING CLOTH.

Specification forming part of Letters Patent No. 39,862, dated September 8, 1863.

To all whom it may concern:

Be it known that we, BARNETT HANSELL, JOHN McCANN, and SAMUEL McCAMBRIDGE, of the city and county of Philadelphia, and State of Pennsylvania, have invented a new and useful Improvement in Machines for Cutting Cloth for Tents and other Purposes; and we do hereby declare that the following is a full, clear, and exact description of the construction and operation of the same, reference being had to the annexed drawings, making a part of this specification, in which—

Figure 1 is a perspective view of the machine. Fig. 2 is a vertical longitudinal section of the same. Fig. 3 is a perspective view of the slotted cutter-bar J. Fig. 4 is a perspective view of the slotted extension-bar J'. Fig. 5 is a perspective view of one of the slitting knives Q, in combination with its stock R. Fig. 6 is a perspective view of the supporting-bar T.

Like letters in all the figures represent the same parts of the machine.

The nature of our invention will be understood by the following description:

We construct a standing frame, A, to receive the several parts of the machine. B is a cylinder, over which the cloth is wound to be cut into the required length. It has a central shaft, C, whose journals D D turn in appropriate bearings in the uprights E E of the standing frame A. F is an endless apron, which encircles the said cylinder B and the roller G, whose journals turn in the uprights of the frame H, the said frame being connected with the frame A' at its lower end by means of the mortises a a and pins b b. The upper end of the frame is adjustable for the purpose of giving proper tightness to the apron F by means of the braces I I, whose lower ends turn on the pins c c and in the mortises d d of the frame A', the upper end of the braces being adjustable by means of the notches f f f f f f of the frame H. The frame A' is made separate from the frame A, so that it may be bolted fast to the floor of the building at any requisite distance from the latter frame to bring the roller G the proper distance from the cylinder B to suit the length of the apron F, which corresponds to the length or lengths of one or more pieces into which the cloth is to be cut. There is a bar, J, to which the ends

of the apron F are confined, one end being passed through the longitudinal slot g and the other through the slot g' and sewed fast to the bar. The pricks h h h h (see Fig. 3) serve for the purpose of attaching the front end of the cloth which is to be cut to the bar J. The inner edge of the slot g also serves as a guide for a knife which is drawn through said slot to cut the cloth into lengths when a sufficient quantity has been wound around the apron for that purpose. There may be two or more of the slotted cutter-bars J connected with the apron F, which may be either at equal or unequal distances, so that the cloth may be cut either of equal or unequal lengths, as may be desired. There are ways K K which serve as supports for the bar J, the ends of which rest upon them while the cloth is being cut into lengths. The legs i i i i have slots j j j j through which the screws k k k k pass and confine the legs to the frame A'. The object of the slots is to vary the ways K K in their elevation and angle to suit any variation which may be made at any time in the length of the apron F. The said apron is only used when the circumference of the cylinder B cannot be conveniently made to suit the lengths into which the cloth is to be cut, and we seldom find occasion to use it except when we cut the cloth into very long lengths. At other times the apron is detached from the machine, and the cloth is wound simply around the cylinder B.

For the purpose of varying the circumference of the cylinder B, in order to vary the length of the pieces into which the cloth is to be cut, there is an extension-bar, J', or, if necessary, there may be several arranged around the cylinder. The bar J' has legs m m, (see Figs. 2 and 4,) which are movable in the grooves n n in the heads of the said cylinder. (See Fig. 2.) The said legs are confined by means of the screws o o, which pass through the slots p p, which lead into the grooves n n. The extension of the bar J' is represented by red lines in Fig. 2. There is a longitudinal slot, g'', in the extension-bar J, for the same purpose as a guide for the knife as the slot g in the bar J.

L L are tension-bars for the cloth M as it is drawn either on the cylinder B or the apron F. They are permanently fastened to the up-

rights C' C' of the frame A. There are adjustable guides N N for the cloth, which have mortises or slots q q (see Fig. 2) equal in length to the distance across the bars L L. They are secured on the said bars by means of the set-screws r r.

P is a tension-roller for the cloth, auxiliary to the bars L L. Contiguous to and in front of the said roller we place any number of knives, Q Q, for cutting the cloth into required widths. These knives have stocks R R, (see Fig. 5,) which fit in the longitudinal groove s of the bar S, which is permanently secured to the uprights C' C' of the frame A. The knives Q Q are adjustable by means of the set-screws t t, which pass through the longitudinal slot u of the bars S.

T is a support-bar for the cloth M to steady the same as it is acted upon by the slitting-knives Q Q. For the purpose of lowering the said bar when a piece of cloth is to be attached to the cylinder B, there is a hole, v, in its rear end, (see Fig. 6,) which fits on a pin or screw in the upright C' at the rear side of the machine. When the bar is in its elevated and acting position, its front end is secured by means of the spring w on the front upright, C'. (See Fig. 1.) Sometimes some of the strips of cloth which are wound around the cylinder B or the apron F are not to be cut into the same lengths as the other strips, and for the purpose of taking them out of the way, as their attached ends come under the cylinder B, after they have passed around the same, we give the ends a turn or two on the roller U, which is made to wind said strips up by means of the band V, connecting said roller with the cylinder B, as seen in Fig. 1.

The operation is as follows: The front end of the cloth being passed around the tension-bars L L and roller P, and caught on the pricks h h h h of the bar J, the cylinder B is turned in the direction of the arrow, which winds the cloth around the apron F, the knives Q Q, in the mean time, slitting it into the required widths; and any one of the strips that is not to be cut of the same length or lengths as the others has its front end disengaged from the bar J, and is wound a turn or two on the roller U, to secure it to the same, the machine having been stopped for that purpose. Then the machine is again started, and when a sufficient quantity is wound on the apron to be cut, the machine is again stopped, with the bar J resting on the ways K K, and a knife is drawn through the slot of said bar, and against the inner edge of the slot, cutting all the strips across that have to be cut into the same lengths, and then the operation of winding and cutting the cloth is again proceeded with, as above described. The cloth that has been wound on the roller U may at any time be taken off of the same and laid aside to be cut alone, or may be transferred to the apron F, or cylinder B, to be cut into suitable

lengths with other cloth, as the operator may deem best. In the former case we take the roller out of its place and slip the cloth from it in a careful manner, so that it may again be placed on it when occasion may require. For the purpose of detaching the roller, the bearing for one of the journals (see Fig. 2) is open and has a shifting support-bar, x, in front to hold it in place, the said bar being held by the screw y at its bottom end, on which it turns, and catching at its upper end between the bent rod z and the upright C', in which one end of said rod is fastened. We, however, usually make the bearings for the journals of the roller in the opposite side of the uprights C' C', which supercedes the necessity of having anything to cover the journal. In case the cloth is to be cut into short lengths, the use of the apron F is dispensed with and the cylinder B is merely used for winding the cloth. When we wish to cut the ends of the pieces of cloth of angular or curved form, or any other form otherwise than square, instead of making the cutter-slot in the extension-bar J' we make it in the periphery of the cylinder B, which has to be of unbroken surface, at least where the slot or slots are formed.

Having thus fully described the construction and operation of the machine for cutting cloth for tents and other purposes, what we claim therein as new, and desire to secure by Letters Patent, is—

1. The construction of the cylinder B, with one or more cutter-slots g'', substantially as described, for the purpose of cutting the cloth into definite and suitable lengths and forms, as above set forth.

2. Combining and arranging the extension bar or bars J' with the cylinder B, for the purpose of varying the circumference of the latter, substantially as described, and for the purpose set forth.

3. Constructing the apron F with the slotted cutter bar J, when combined and arranged with the cylinder B, substantially in the manner and for the purpose above set forth.

4. The combination of the knives Q Q with the cylinder B, when arranged and operating substantially as described.

5. The combination and arrangement of the reciprocating roller U with the cylinder B, substantially as and for the purpose above set forth.

6. The arrangement of the support-bar T in relation to the knives Q Q and cloth M, substantially as described.

In testimony that the above is our invention we have hereunto set our hands and affixed our seals this 17th day of June, 1863.
